INTERMITTENT GRIP DEVICE

Fred C. Arey, Oak Park, Ill., assignor to Vulcan
Soot Blower Corporation, a corporation of
Pennsylvania

Application October 31, 1932, Serial No. 640,373

10 Claims. (Cl. 74—116)

Specifically considered, the present invention has for its object to produce a simple and novel means for turning a tubular soot cleaning element step by step.

5 Sometimes the heat to which tubular soot cleaning elements for boiler tubes are subjected causes them to become distorted, thereby necessitating the application of considerable force to turn the same. In one of its aspects, the present invention may be said to have for its object to produce a simple and novel turning means for such a cleaning element, or other element, in which the motive force is multiplied many times before being applied to the element to turn the same.

10 It is, of course, possible to secure a desired multiplication of the applied force by using levers of the proper length and ratios as to their arms. However, the space available for the operating means by which a cleaning element or other element is to be turned is often limited so that long levers could not be employed even if they were not otherwise objectionable. Viewed in one of its aspects, the present invention may be said to have for its object to produce in a simple and compact form a step by step driving mechanism in which the leverage or multiplication of force is very much greater than has heretofore been obtainable without the employment 15 of objectionably long levers.

20 In carrying out my invention, I fix on the element to be turned a ratchet wheel and mount on said element beside the ratchet wheel a pawl-carrying arm free to swing on said element. On 25 the arm is pivoted a pawl provided with a slot or other means including two parallel separated guiding surfaces. The pawl and the arm carrying the same are driven by a pin or roller extending into the slot or between the guide surfaces on the pawl and having a diameter approximately equal to the width of the slot or the spacing between the guide surfaces. The pin or roller is mounted and supported so as to be capable of revolving bodily about an axis spaced 30 apart from and parallel to the axis of the pin or roller and the axis of the element to be turned. The radius of the path in which the pin or roller travels is made short so that, as the pin or roller travels in a circle, continuously in one 35 direction, it drives the pawl and the pawl-carrying arm in a manner to give the element to be turned a step by step movement, one step for each complete revolution of the pin or roller. This arrangement is particularly useful for the 40 purpose of first driving the element to be turned

in one direction and then in the other direction; the pawl being made double-ended so that, as long as the driving pin or roller revolves about its axis of rotation in one direction, the element to be turned moves step by step in the same direction whereas, when the direction of the turning movement of the pin or roller is reversed, the member to be turned will also begin to move step by step in the reverse direction.

45 Therefore viewed in one of its aspects, the present invention may be said to have for its object to produce a simple and novel mechanism for turning an element step by step in either direction by means of a continuously rotating crank pin or the like, the direction in which the element turns depending on the direction in which the crank pin or the like turns and changing with the same.

50 Viewed in another of its aspects, the present invention may be said to have for its object to produce a simple and novel reversing step by step drive in which a double-ended pawl is hung upon a swinging arm, the pawl and the arm being driven by a continuously rotating crank pin or the like, turning first in one direction and then in the other, wherein the proper end of the pawl will always be engaged with the ratchet wheel at the beginning of a working stroke, without moving the pawl-carrying arm until such engagement is 55 effected.

50 The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a longitudinal central section, 40 through the head end of a soot cleaning element embodying the present invention; Fig. 2 is an end view of the apparatus; Fig. 3 is a section on line 3—3 of Fig. 1; Fig. 4 is a top plan view of the pawl, pawl carrier and the operating member therefor, the bearing for the operating member being shown in section; and Fig. 5 is a bottom plan view of a fragment of the cleaning element, showing the ratchet wheel, the pawl carrier, and the brake for the latter.

55 In the drawings the invention is illustrated as applied to a tubular soot cleaning element and, for the sake of brevity, the detailed description will be confined to this particular use; but it will, of course, be understood that the invention may

be applied to effect a step by step movement of any other element.

Referring to the drawings, 1 is a tubular cleaning element adapted to discharge jets of steam or other cleaning fluid against the tubes of a boiler of which only a fragment of the boiler setting 2 is shown. 3 is a tubular extension of the cleaning element proper and may be regarded as forming a part of the latter. Connected to the free end of the member 3 is a hollow head 4 which supplies the cleaning fluid; the head being stationary and the member 3 being rotatable in the head. All of these parts are old. The present invention has to do with the mechanism for turning an element which, in the present instance, is the tubular cleaning element, about its long axis. In the arrangement shown, there is keyed to the cleaning element device a ratchet wheel 5, the ratchet wheel being preferably on the member 3. 10 Loose on the member 3, beside the ratchet wheel, is a pawl-carrying arm 6 having a disk-like thickened hub portion 7 provided with a projecting circumferential bead 8. This arm carries at its outer end a pawl 9; the pawl being mounted on a journal or pivot pin 10 fixed to the arm 6 and lying parallel with the cleaning element. The pawl is provided with two dog members 11 and 12 diverging from each other. The parts are so proportioned that, when the pawl, which lies in the plane of the ratchet wheel, is symmetrically disposed with respect to a line passing through the pivotal axis thereof and through the axis of the cleaning element, as shown in Fig. 3, both dogs are out of engagement with the ratchet wheel. 15 Consequently, when the pawl is tilted in the clockwise direction, as viewed in Fig. 3, the dog 12 will move into engagement with the teeth on the ratchet wheel, whereas the dog 11 will lift still farther away from the wheel. When the pawl is tilted in the opposite direction, the dog 11 engages with the ratchet teeth and the dog 12 is elevated. With this arrangement, by properly shifting the pawl on its supporting arm and oscillating the arm, the ratchet wheel may be 20 turned step by step in either direction.

Novel means are provided for oscillating the pawl on its supporting arm and for oscillating the arm through working and return strokes. In the specific arrangement illustrated, the driving member is a rotatable shaft 14 parallel to the cleaning element and having its long axis spaced apart from the axis of the cleaning element a radial distance slightly greater than the radial distance between the pivotal axis of the pawl on its 25 supporting arm and the axis of the cleaning element. This shaft is supported in bearings in a bracket or pedestal 15 rising from the head 4 and a heavy plate 16 forming one wall of a housing for the pawl and ratchet mechanism and connected to the head 4 by means of long, strong bolts 17 surrounded by sleeves 18 that space the member 16 and the head apart from each other. Spaced apart from the wall 16, and lying on the 30 opposite side of the pawl and ratchet mechanism from that on which the wall 16 is located, is a second wall 19 which, with a connecting annular wall 20 of sheet metal, completes the casing or housing for the pawl and ratchet mechanism. On the end of the shaft 14, within this casing or housing, is a short crank 21 having thereon a crank pin 22 whose axis is spaced only a short distance from the axis of the driving shaft 14. In order to reduce friction, I prefer to mount on the crank pin a wheel or roller 23 supported by 35 anti-friction bearings. This wheel or roller ex-

tends into a slot 24 in the pawl, so that the pawl and the crank may be said to have a pin and slot connection with each other. The slot 24 is in the form of a groove of the same width as the diameter of the wheel or roller 23, so placed that its longitudinal center line passes through the pivotal axis of the pawl and bisects the angle between the two ends or dogs. The radius of the path of travel of the crank pin is somewhat greater than the distance between the pivotal axis of the pawl and the axis of the driving shaft, extended, when the parts are in such positions that the axes of the cleaning element, of the driving shaft, and of the pivot or journal for the pawl are all in the same plane. Consequently, when the driving shaft is turned in either direction, the crank pin at times lies outwardly from the pivot for the pawl, and sometimes inwardly therefrom. As the driving shaft revolves, carrying the crank pin with it, the crank pin acts on the 10 sides of the trough in the pawl and causes the pawl to swing on its supporting arm.

Assuming that the parts are in the positions indicated in Fig. 3 and that the driving shaft is being operated to cause the crank pin to travel in the clockwise direction, it will be seen that the action of the crank pin will be to swing the pawl in a clockwise direction, provided that there is less resistance to movement on the part of the pawl than to swinging movements by the pawl-carrying arm. Should the pawl-carrying arm be movable under a lesser pressure than that required to tilt the pawl, the only result would be an oscillation of the pawl-carrying arm without producing any engagement of the pawl with the ratchet wheel. However, if the pawl-carrying arm be held against rotation until the dog 12 has been swung down into engagement with the teeth on the ratchet wheel, then a continued movement of the crank pin will cause the pawl and the arm to travel ahead together, with the pawl driving the ratchet wheel. I have therefore provided a brake that holds the pawl-carrying arm against turning movements sufficiently to insure that the pawl may make its necessary rocking movements on the pawl-carrying arm while the latter is standing still; but not offering sufficient resistance to turning or swinging movements of the pawl-carrying arm to interfere with efficient operation of the latter. In the arrangement shown, the brake consists of two arms, 25 and 26, lying on opposite sides of the cleaning element in the plane of the hub portion of the pawl-carrying arm. Corresponding ends of the arms 25 and 26 are provided with seats 27 partially embracing stationary abutments 28 in the housing or casing, to permit the arms to rock. The opposite ends of the arms are connected together by a tension spring 29. Each of the arms 25 and 26 has thereon a brake shoe 30 grooved to fit over the annular rib or projection 8 and thus be held against slipping off the hub of the pawl-carrying arm in the lateral direction.

Consequently, when the crank pin travels in the clockwise direction, as viewed in Fig. 3, with the parts initially positioned as there shown, the brake device holds the pawl-carrying arm stationary, so that the first part of the movement of the crank pin results in a tilting or swinging of the pawl to bring the dog 12 into engagement with the teeth on the ratchet wheel. Further movement of the crank pin results in a clockwise turning movement of the cleaning element. The turning movement of the ratchet wheel ceases after the crank pin has traveled through 75

an angle somewhat greater than ninety degrees and then a slight counter-clockwise swinging movement of the pawl about its pivot takes place. However, as soon as the center of the crank pin 5 passes below the arc-shaped path of the pivot for the pawl, the pawl is again swung in the clockwise direction before any pressure tending to drive the ratchet wheel backwards can be exerted. After the crank pin has made half a 10 revolution it is pressing against the left-hand side of the wall or trough or slot, either below or above the arc-shaped path in which the pivot of the pawl travels, thus causing the dog 12 to be 15 swung into contact with the periphery of the ratchet wheel and the pawl-carrying arm to swing toward the left. During the last half of the movement of the crank pin through one complete revolution, the arc of the crank pin passes on the other side of the pawl pivot pin, causing 20 a slight clockwise pressure on the pawl while the pressure on the pawl-carrying arm is counter-clockwise; thus holding the dog 11 out of engagement with the ratchet wheel on the return stroke of the pawl arm. As long as the driving shaft 25 continues to be turned in the clockwise direction, the cycle just described will be carried out during each revolution of the shaft, and the cleaning element will be driven in the clockwise direction step by step, one step during each revolution 30 of the driving shaft. However, because of the peculiar construction and arrangement of the parts, when the direction of rotation of the driving shaft is reversed, the dog 11 of the pawl becomes the active one and the cleaning element 35 is turned step by step in the counter-clockwise direction.

The driving shaft is turned by means of a wheel or sheave 32 of comparatively large diameter, fixed to the outer end of the shaft. In the 40 peripheral trough of the wheel are sprocket teeth 33 engaged with an endless chain 34. By pulling upon one of the depending stretches or runs of the chain, the driving shaft will be caused to turn in one direction. When the other stretch or run 45 is pulled down, the direction of rotation of the driving shaft is reversed. The driving wheel or sheave, without being so large as to destroy the idea of compactness in the construction as a whole, may have a diameter much greater than 50 the radius of the crank that operates on the pawl and pawl-carrying arm. Again, the crank pin acts on the long arm of the lever in driving the pawl and ratchet device. Consequently, the force of a pull on the chain is multiplied many 55 times before being transmitted to the element to be turned; thus making it easy to turn the cleaning element even though the latter offers great resistance because of being distorted, or for any other reason. This powerful driving effort, as 60 heretofore explained, is obtained without making any of the over-all dimensions of the structural apparatus large. For the sake of comparison, the driving mechanism of Patent No. 1,590,300, of June 29, 1926, may be regarded as representing 65 the old practice. In order to secure a lever arm of about 8 inches in the mechanism of that patent, the over-all width must be about 18 inches. With the present construction, having an over-all width of about 7 inches, which is the diameter 70 of the sprocket wheel, the same effect is obtained as though the lever arms of the mechanism in Patent No. 1,590,300 were 25 inches long, producing an over-all width of between four and five feet.

75 In the arrangement shown, the double-ended

pawl is so proportioned that the pivotal axis thereof passes through the center of gravity, whereby the pawl is balanced and will remain in any position into which it may be placed. While the balanced characteristic is not essential for 75 the successful operation of the device, it is useful whenever the apparatus must be so set that the pawl-carrying arm 6 will not be vertical when in the neutral position which it occupies in Fig. 3. In other words, it may sometimes be necessary to 10 set the head in a position in which it is turned bodily, either in a clockwise direction or in a counter-clockwise direction, about the axis of the cleaning element, from the vertical position illustrated in the drawings. 15

It will, of course, be evident that the cleaning element may be turned through any desired complete number of revolutions, step by step, by simply pulling on the proper vertical stretch or run of the chain. Ordinarily, in the case of soot 20 cleaning elements, it is not necessary or desirable to turn them through complete revolutions, as otherwise there would be no necessity for reversing their direction of angular movements. On the other hand, after a cleaning element has been 25 turned through an angle of less than 360°, it is the practice to turn it back again through the same angle. I have therefore provided means whereby the turning movement of the cleaning element, in either direction, may be arrested after 30 any desired angular distance has been traversed. To this end, I have provided the ratchet wheel 5 with a projecting hub 35 having distributed 35 around the periphery a series of radial holes 36. In the face of the ratchet wheel, at the inner 35 end or base of the hub, is an annular groove 37. Blocks 38, adapted to rest on the periphery of the hub, and having toe sections 39 adapted to enter the groove 37 serve as adjustable stop elements adapted to engage with a suitable stationary 40 stop element 40 on the wall member 16. I have shown only one of these blocks, because the second block will be just like the first. Each block is provided with a screw stud 41 extending radially through the same and adapted to be 45 screwed into any one of the openings 36 in the hub. When the blocks are secured to the hub and the ratchet wheel is turned, the stationary stop 40 lies in the path of travel of the blocks; so that, after the ratchet wheel has been turned 50 through a predetermined angle in one direction, one of the blocks will engage with the stationary stop and, after the cleaning element has been turned in the opposite direction through the same angle, the second block will strike the stationary stop. Therefore, the operator simply 55 pulls the chain until it will move no farther, whereupon he will take hold of the opposite stretch or run of the chain and pull it to the limit of the movement permitted by the stop device. 60

If desired, a guard may be provided to hold the two stretches or runs of the chain in proper spaced relation to each other just after leaving the wheel or sheave. In the arrangement shown, there is a V-shaped bracket 42 loosely hung on the driving shaft 14 between the pedestal 15 and the wheel or sheave; the driving shaft passing through the apex of the bracket. On the free ends of the arms of the bracket are heavy ring-like projections lying in planes at right angles to the body of the bracket. The two runs of the chain are threaded through the openings in these projections and are thereby held in spaced relation to each other, while being permitted to 70 75

move or swing laterally in the plane of the wheel or sheave.

It will thus be seen that I have produced a simple, compact pawl and ratchet driving mechanism in which a powerful lever action is secured to aid in turning an element; in which a step by step turning movement results from a continuous movement in one direction of the driving member; and in which a reversal of the step by step movement is effected through a mere change in the direction of movement in the driving mechanism.

While I have illustrated and described with particularity only a single preferred form of my invention, I do not desire to be limited to the exact structural details thus illustrated and described; but intend to cover all forms and arrangement which come within the definitions of my invention constituting the appended claims.

20 I claim:

1. In combination, a member to be turned step by step in either of two directions, a ratchet wheel fixed to said member, an element mounted for oscillation about the turning axis of said member, 25 a double-ended pawl pivoted on said element in position to be swung into and out of engagement with said ratchet wheel, a short crank rotatable in either of two directions about an axis parallel with the aforesaid axis and farther away 30 from the latter than the pivot of the pawl, a crank pin on said crank, and guides on said pawl in sliding engagement with opposite sides of said crank pin.

2. An element adapted to be turned step by 35 step in either of two directions, a driving member adapted to be continuously rotated, a ratchet wheel fixed to said element, a pawl arm adapted to swing about the axis of said element, a double-ended pawl on said arm adapted to cooperate 40 with the ratchet wheel to turn said element in one of said directions or the other depending upon which end of the pawl engages with the ratchet wheel, and a pin and slot connection between said pawl and the driving member including a crank pin on said member.

3. An element adapted to be turned step by 45 step in either of two directions, a driving member adapted to be continuously rotated, a ratchet wheel fixed to said element, a pawl arm adapted to swing about the axis of said element, a balanced double-ended pawl on said arm adapted to cooperate with the ratchet wheel to turn said element in one of said directions or the other depending upon which end of the pawl engages 50 with the ratchet wheel, and a pin and slot connection between said pawl and the driving member including a crank pin on said member.

4. An element adapted to be turned step by 55 step in either a backward or a forward direction, 60 a ratchet wheel fixed to said element, a pawl arm adapted to swing about the axis about which said element turns, relatively to said element, a double-ended pawl pivotally mounted on said arm in position to cooperate with said ratchet 65 wheel, one of the ends of the pawl being adapted to turn the ratchet wheel in one direction and the other end of the pawl being adapted to turn the ratchet wheel in the opposite direction, a driving member rotatable about an axis parallel 70 to the axis of the ratchet wheel and spaced a considerable distance apart from said axis, said pawl having therein a radial slot, a crank pin on said driving member spaced apart a short distance from the axis of rotation of the driving member and projecting into said slot, said slot

being at least as long as the diameter of the path of travel of the crank pin.

5. In combination, a ratchet wheel, a pawl arm, means for supporting the wheel and the arm adjacent to each other for independent angular movements about the axis of the ratchet wheel, a double-ended pawl pivoted on said arm in position to permit either end to be swung into operative relation to the teeth on the ratchet wheel to permit the wheel to be turned in either direction, said pawl having a radial slot at the center, a driving member rotatable about an axis parallel to the axis of the ratchet wheel, and a crank pin carried by said driving member and projecting into the slot in the pawl, said slot being long enough to permit the crank pin to remain therein during the rotation of the driving member.

6. In combination, a ratchet wheel, a pawl arm, means for supporting the wheel and the arm adjacent to each other for independent angular movements about the axis of the ratchet wheel, a double-ended pawl pivoted on said arm in position to permit either end to be swung into operative relation to the teeth on the ratchet wheel to permit the wheel to be turned in either 25 direction, said pawl having a radial slot at the center, a driving member rotatable about an axis parallel to the axis of the ratchet wheel, and a crank pin carried by said driving member and projecting into the slot in the pawl, said slot being 30 long enough to permit the crank pin to remain therein during the rotation of the driving member, and the parts being so proportioned that the path of travel of the center of the crank pin passes entirely around the pivotal axis of 35 the pawl.

7. A member adapted to be driven step by step in either of two directions, a driving member adapted to be moved continuously in either of two directions, a ratchet wheel on the first of 40 said members, a double-ended pawl cooperating with said ratchet wheel to cause one end of the pawl to drive the wheel in one direction and the other end of the pawl to drive the wheel in the opposite direction, a support for the pawl adapted 45 to oscillate through a small angle, and means driven by said driving member and engaged directly with the pawl to oscillate said support and cause one end of the pawl to act as the wheel-driving element as long as the driving member 50 is moving in one direction and to cause the other end of the pawl to act as the wheel-driving element whenever the driving member is moving in the other direction.

8. In combination, a ratchet wheel, an oscillatory pawl arm, a double-ended pawl pivoted on said arm in position to permit either end to be swung into operative relation to the teeth on the ratchet wheel, whereby the ratchet wheel may be turned step by step in either direction, 60 a driving member adapted to be rotated in either direction about an axis parallel to the axis of the ratchet wheel; and means, including a pin carried by said driving member at some distance from the axis of rotation of the latter, and guide 65 elements on the pawl with which said pin slidably engages, to cause said pawl to be oscillated on said pawl arm to bring one end of the pawl or the other into engagement with the ratchet wheel, depending upon the direction in which the 70 driving member is turning, whereby the ratchet wheel will be driven step by step in one direction while the driving member is rotated continuously in one direction and the ratchet wheel will be driven step by step in the opposite direc- 75

tion when the direction of rotation of the driving member is reversed.

9. A ratchet wheel adapted to be turned step by step in either direction, a driving member adapted to be continuously rotated in either direction, a pawl arm adapted to oscillate through a small angle, a double-ended pawl on said arm in position to cooperate with the ratchet wheel to turn the latter in one direction or the other depending upon which end of the pawl engages with the ratchet wheel, and a pin and slot connection between said pawl and the driving member including a slot in the pawl and a crank pin on the driving member.

10. A ratchet wheel adapted to be turned step

by step in either direction, a driving member adapted to be continuously rotated in either direction, a swinging pawl arm, a double-ended pawl on said arm adapted to cooperate with the ratchet wheel to turn the same in one direction or the other depending upon which end of the pawl engages with the ratchet wheel, and a driving connection between said pawl and the driving member including an elongated guide element located radially and at the center of the pawl, and a part mounted on the driving member at some distance from the axis of rotation of the latter and slidably interlocked with the guide element on the pawl.

FRED C. AREY.
